UNITED STATES PATENT OFFICE.

FRANCIS LEONARD ORR, OF THURMAN, IOWA.

VALVE.

No. 905,745.

Specification of Letters Patent.

Patented Dec. 1, 1908.

Application filed July 8, 1907. Serial No. 382,604.

To all whom it may concern:

Be it known that I, FRANCIS LEONARD ORR, a citizen of the United States, and a resident of Thurman, in the county of Fremont and 5 State of Iowa, have invented certain new and useful Improvements in Valves, of which the following is a specification.

This invention has for its object, a new and improved valve, designed for use with 10 starting means of gas or gasoline engines, of the internal combustion type, and the particular form of starting means employing air, or gas, stored under pressure adapted in use for starting the engine in operation, by 15 means similar in form to means disclosed in Letters Patent No. 809,211 granted to me Jan. 2, 1906, and No. 837,953 granted to me Dec. 11, 1906.

In my allowed applications, Serial Nos. 20 356,019, and 367,346, air or gas engine starting means is shown and described with which the improved valve forming the subject of this invention is also adapted for use.

The present invention is designed as an 25 improvement on the said Letters Patent, and the engine starting means disclosed in my allowed applications, and also other similar engine starting means employing stored pressure of air, or gas for use as motive 30 power to boost or force the engine in operation.

The particular object of my present invention, is a valve adapted for arrangement in the fluid passage-way connecting the engine 35 cylinder and storage-tank shown and described in my patents and allowed applications above referred to.

The valve is peculiar in construction and operation in being constructed for adjustment to closing position, cutting off flow of 40 air or gas through the passage-way connecting the storage-tank with the interior of engine cylinder, at all times during operation of the engine save upon ignition of the engine charge, at which time it is designed to 45 be forced from its seat permitting a portion of the exploded, or exhaust gases to flow into its receiving tank and be compressed therein by operation of the engine piston during its 50 exhaust stroke.

It is intended to provide the valve with tension means whereby it will automatically seat to closing position when pressure of the exploded charge lowers to atmospheric pressure 55 or pressure of gas stored in the receiv-

ing tank shall exceed atmospheric pressure. In other words, a portion only of the exhaust is forced into the storage tank, the other portion thereof being forced through the regular exhaust port.

To the end above briefly defined, I have invented the new and improved valve attachment for engine starting means, hereinafter fully described, and shown by the accompanying drawing, the features of novelty being pointed out in the appended claims.

In the drawing Figure 1 is a perspective view, in illustration of my invention, the view is practically diagrammatic and intended simply to show connection and arrangement of the engine starter means, with my improved controller valve located at the engine cylinder end of the tubular passage-way, providing communication between the storage-tank and the combustion end of the engine cylinder and Fig. 2 a central longitudinal sectional view of the valve.

In the preferred form of my invention I employ a valve A and locate same on the combustion end of the cylinder B of an internal combustion engine.

C designates a storage tank made communicating with the interior of combustion end of the cylinder B, by means of a tubular passage-way D, the latter providing communication with the cylinder, B, through the controller valve as indicated by the series of connected arrows in Fig. 2, that is, when the valve is at open position. It is designed to provide the tank C with an indicator E whereby pressure of air, or gas, in the tank, may be ascertained at any time, and the tubular passage-way D may be provided with one or both cut-off valves F, G, the former being located near the controller valve A, and the latter near the storage tank C.

I would now refer to valves F, G, shown located in the tubular passage-way D. The valve F is simply a common stop-cock which enables the engine to be started a little easier than by turning the valve A, yet its use is not necessary, and the valve G is a common globe valve intended for use as an extra precaution, to hold the air or gas, in the tank C, should the turning plug valve F leak. When air or gas is being forced into the tank C, by action of the engine-piston, the valves F, G, should be wide open. The

controller valve A is constructed with a hollow body H, inclosed by a casing I, having therebetween a water-space J.

The casing I is provided with nipples K, L, adapted respectively for attachment of water circulating pipes K', L',—see Fig. 1. The pipes K', L', form a part of engine water cooling system commonly employed with internal combustion engines, and being well understood, need no further description than to say that they are suitably connected with the water supply pipes leading to and from the engine jacket. The valve-body H, has a common form of detachable plug M, and the latter is longitudinally bored and screw-threaded adapted to receive a stem N, having an enlargement O at its inner end. On the stem enlargement O is arranged a cap P secured by a collar O² as shown by Fig. 2. It is intended that cap P and collar shall have longitudinal sliding movement on the stem-head O for the purpose hereinafter appearing.

Upon reference to Fig. 2 it will be noticed that the stem N is longitudinally bored, adapted to receive a rod R whose inner end is designed to rest against the inner side of the cap P. The cap P is provided with a packing disk S, adapted to be seated on a valve-seat T, in the body-portion H. It will be understood that the cap P provides a valve for closure of the opening through the valve-seat T, and the same will be understood without further description. The outer end 35 of the valve-stem N is provided with a hollow detachable hand device U adapted to receive a spring V having balls W, W' at its ends as shown. It will be further noticed that the ball W' is arranged in contact with the outer end of the rod R, and that a set-screw A' is utilized whereby to regulate tension of the spring V.

In the use of my invention, assuming the tank C is stored with sufficient pressure of air or gas and it is desired to start the engine in operation, the valves F, G, are first opened and then the hand device U of the controller A is turned until the valve, or cap P is unseated, thereby opening up passage-way leading from the tank C, through the tubular passage-way D, the valve seat T and into the combustion chamber of the engine cylinder B. It will be understood that the controller valve A is arranged on the engine cylinder providing the continuous passage-way for flow of the air, or gas as described. Now it is obvious that pressure of air or gas let into the engine, in rear of its piston, shown by dotted lines in Fig. 1, will force the piston forward, that is, oppositely in movement to its in stroke, indicated by the arrow, and thereby, through movement of connecting parts, start the engine fly-wheel in motion. Before the engine piston has made a complete stroke, as above de-

scribed, the valve P is tightly seated through obvious operation of the hand-device U.

It is designed that tension of the spring V shall exert force sufficient to hold the valve P closed against charge compressing power 70 of the engine piston, and that being so, obviously, the boosting or starting flow of air or gas fed into the cylinder as stated, will be forced out through the usual exhaust port, as usual in the scavenging operation of 75 internal combustion engines. After the engine is started as described, the hand device U is turned slightly, thereby to slightly reduce tension of the spring V on the adjacent end of the rod R. It is apparent that the 80 valve P will still remain seated since it is free to slide on the stem-head O, and it is made to thus slide through pushing movement of the rod R. Tension of the spring V is regulated by the set-screw A', and the 85 same is adjusted adapted through operation or endwise movement of the rod R, to hold the valve P securely seated against escape of a compressed motive charge before it is ignited, that is to say, the valve P is yielding 90 held seated adapted to be unseated by increased force of the exploded charge, over normal force of an unfired compressed charge. Now with my invention, at each 95 exhaust stroke of the engine piston, a portion of the exploded gases is forced into the storage tank through lifting or puppet action of the valve P, and the storing action continues until the pressure in the tank C equals the pressure of an exploded charge in the 100 engine cylinder, at which time the valve P will remain seated and the whole exploded charge pass off through the cylinder exhaust port.

Further description of the use of my 105 invention is deemed unnecessary since the above description will render it fully understood.

I claim:

1. The combination in an engine starter, 110 of a storage tank, a tubular passage-way providing communication between said tank and the engine-cylinder, a valve located in the tubular passage-way, the valve being constructed with an operating stem adapting 115 it to be set at closing position, a movable seating cap on the inner end of the valve stem, yielding means on the outer portion of the valve stem, and means operatively connecting said cap and yielding means. 120

2. In an engine starter utilizing stored air or gas as power for boosting the engine into operation, a valve adapted to control supply of the boosting medium, said valve being constructed with a hollow body having a 125 valve-seat therein, a reciprocating valve-stem, a movable seating cap on the inner end of said stem, tension means on the outer end of the stem, and a slidible rod located between said cap and tension means. 130

3. In an engine starter of the character described, a valve constructed with a hollow body having a valve-seat therein, a reciprocating valve-stem, a movable seating cap on the inner end of said stem, a tension spring on the outer end of the stem, a slideable rod, located connecting said spring and cap, and means whereby to regulate pressure of the tension spring.
